COMBINED SHIPPING AND DISPLAY PACKAGE FOR DISHES OR THE LIKE

David J. Freiman, Corning, N.Y., assignor to Corning Glass Works, Corning, N.Y.

Filed Sept. 30, 1970, Ser. No. 25,280

Term of patent 14 years

Int. Cl. D9—03

U.S. Cl. D9—250

Fig. 3

Fig. 4

FIG. 1 is a top plan view of a combined shipping and display package for dishes or the like embodying my new design.

FIG. 2 is an end elevational view as viewed from the lower end of FIG. 1 along line 2—2, the opposite end view being identical.

FIG. 3 is a bottom plan view.

FIG. 4 is a side elevational view along line 4—4 of FIG. 1, with the opposite side being a mirror image.

I claim:

The ornamental design for a combined shipping and display package for dishes or the like, as shown and described.
